SPECTACLE FRAME

Frances R. Nesselroth, Flushing, N. Y., assignor
to The Kono Manufacturing Company, Wood-
side, N. Y., a firm

Application December 13, 1948, Serial No. 150,127

Term of patent 14 years

(Cl. D57—1)

To all whom it may concern:

Be it known that I, Frances R. Nesselroth, a citizen of the United States of America and resident of Flushing, county of Queens, and State of New York, have invented a new, original, and ornamental Design for a Spectacle Frame, of which the following is a specification, reference being had to the accompanying drawing, forming a part thereof, in which

Fig. 1 is a front elevational view of a spectacle frame, embodying my design;

Fig. 2 is a top view thereof; and

Fig. 3 a side view.

The essential features of my design for a spectacle frame reside in the particular type of ornamentation shown thereon and the arrangement thereof, as seen most clearly in Fig. 1 on the drawing.

I claim:

The ornamental design for a spectacle frame, as shown and described.

FRANCES R. NESSELROTH.
